UNITED STATES PATENT OFFICE.

SANTO E. P. MATACOTTA, OF NEW YORK, N. Y., ASSIGNOR OF ONE-HALF TO EVANGELO OTIDYS, OF NEW YORK, N. Y.

SMOKING-PIPE.

1,147,527.

Specification of Letters Patent. Patented July 20, 1915.

Application filed June 26, 1914. Serial No. 847,437.

To all whom it may concern:

Be it known that I, SANTO E. P. MATA-
COTTA, a citizen of the United States, and a
resident of the city of New York, borough
5 of Brooklyn, county of Kings, and State of
New York, have invented a new and Im-
proved Smoking-Pipe, of which the follow-
ing is a full, clear, and exact description.

This invention relates to improvements in
10 smoking pipes, and particularly to an im-
proved device for filtering the smoke as it
passes from the bowl to the mouth.

Another object of the invention is to pro-
vide an improved filtering device arranged
15 on the order of a cartridge so that the same
may be inserted and removed at any time.

A further object of the invention is to
provide an improved cartridge structure de-
20 signed to be inserted into the smoke passage
of a pipe which is provided with one or more
compartments filled with cotton, whereby
the nicotin is caught as the same passes along
the stem of the pipe.

In the accompanying drawings—Figure 1
25 is a longitudinal vertical section through a
pipe showing an embodiment of the invention,
the mouth piece being shown in full
lines; Fig. 2 is a sectional view through a
cartridge embodying the invention, the same
30 being shown on an enlarged scale; Fig. 3 is
an end view of one of the partitioning mem-
bers in the cartridge shown in Fig. 2; Fig. 4
is a section through Fig. 3 on line 4—4; Fig.
5 is a top plan view of the structure shown
35 in Fig. 2; Fig. 6 is a section through Fig. 5
on line 6—6; Fig. 7 is a view similar to Fig.
1 but disclosing a slightly modified form of
the invention.

Referring to the accompanying drawings
40 by numerals, 1 indicates the bowl of a pipe
of any desired kind, and 2 the stem. Con-
nected with stem 2 is a mouthpiece 3 of any
desired structure. The mouthpiece 3 is pro-
vided with an extension 4 for fitting into the
45 stem 2 in the usual manner. The bore of the
stem 2 which receives extension 4 is of a suf-
ficient size for receiving a cartridge 6. The
cartridge 6 comprises a tubular member 7
formed with apertures 8, 9 and 10, and pro-
50 vided with division walls 11, 12, 13 and 14,
these division walls being preferably held in
place by friction though they may be sol-
dered or otherwise secured in place if de-
sired. These division walls together with
55 tubular member 7 form chambers 15, 16 and

17 for receiving filtering mediums 18, 19 and
20, which filtering mediums are preferably
cotton. The walls or partitioning members
11 to 14, inclusive, are formed as shown in
Figs. 3 and 4, namely, of disks provided
60 with a plurality of apertures 21 and a cen-
tral aperture 22. It is evident that the shape
and arrangement of the apertures may be
changed, and if desired only a single aper-
ture provided, though a plurality of open-
65 ings is more desirable as it causes a better
distribution of the smoke through the filter-
ing medium. The openings 8, 9 and 10 are
for allowing the ready insertion and re-
moval of the bunches of cotton 18, 19 and
70 20. The bore 23 in stem 2 which receives the
extension 4 is provided with a tapering end
24 merging into the smoke passageway 25
which enters bowl 1. The distance between
the end of the extension 4 when the mouth-
75 piece 3 is in position and the tapering end
24 is slightly more than the length of the
cartridge 6, whereby the cartridge will have
ample space and may be easily inserted and
removed. The cartridge 6 is preferably
80 made slightly smaller than the bore so as to
provide a reasonably snug fit but sufficient
space to admit of easy insertion and removal
even when the pipe and cartridge have been
heated.

The structure shown in Figs. 2, 5, 6 and 7
is of a slightly modified form of the inven-
tion in which similar reference numerals
will be used except for the modified part.
As shown in Figs. 2 and 5 the tubular mem-
90 ber 7 is provided with a threaded end 5 so
as to fit over the threaded extension 4'
shown in Fig. 7. Aside from this difference
the cartridge shown in Fig. 2 is the same
as shown in Fig. 1. As clearly disclosed in
95 Fig. 7 the bore 23 is formed with an en-
largement 23' for receiving an enlarged por-
tion 26 of the mouthpiece 3, while the
threaded extension 4' fits into the threaded
portion 5 of cartridge 6. This form of the
100 invention allows the removal of the car-
tridge 6 when the mouthpiece is removed so
as to be cleaned and replenished with a fil-
tering medium. This form of the invention
also allows the use of the pipe without using
105 the cartridge 6 in a similar manner to the
way the pipe shown in Fig. 1 may be used.

In the drawing and description the same
have disclosed an embodiment of the inven-
tion applied to pipes, but it will be evident
110

that the same could be readily applied to cigar and cigarette holders instead of pipes without departing from the spirit of the invention.

5 It is to be noted that by the way the various parts are formed the cartridge may be easily and quickly removed and again inserted so as to be maintained in a cleaned condition and thereby produce a very sanitary construction as well as means for removing the nicotin from the tobacco during the smoking operation.

What I claim is—

- 15 1. In a smoking pipe of the character described, a bowl, a stem extending from said bowl provided with a bore in communication with said bowl, a mouthpiece and a cartridge fitting into said bore, said cartridge comprising an inclosing casing, a plurality of partitioning plates having a plurality of apertures therein for distributing the draft, and an independent filtering medium arranged in each of the compartments formed by said casing and said partitioning plates.
- 20 2. In a filtering device for smoking pipes, a bodily removable cartridge formed with a plurality of openings in one side, a plurality of partitioning walls arranged in the cartridge so as to present an independent room opposite each of said openings and a filtering medium of cotton arranged in each of said rooms, said partitioning walls being
- 25 30

provided with a plurality of spaced perforations so as to distribute the draft substantially evenly to said filtering medium, and 35 said openings in the cartridge providing an entrance for said filtering medium.

3. In a removable filtering device for smoking pipes, a cartridge provided with a tubular member designed to be inserted into 40 the smoke passageway of a pipe, said tubular member having a plurality of openings in one side, a plurality of partitioning members arranged in said tubular member, said partitioning members being arranged in 45 the space between said openings so as to divide the tubular member into rooms opposite said openings, each of said openings presenting an entrance for a filtering medium, each of said partitioning members being provided with a centrally arranged aperture, and a plurality of apertures surrounding said central aperture for distributing the draft to the respective rooms, and a filtering medium arranged in each of said 50 rooms.

In testimony whereof I have signed my name to this specification in the presence of two subscribing witnesses.

SANTO E. P. MATA COTTA.
